SUPPORT FOR ELONGATED, TENUOUS ARTICLES

Foster H. Guthrie, Newark, Ohio, assignor to The Larsen Manufacturing Co., Newark, Ohio, a corporation of Ohio

Filed Mar. 14, 1966, Ser. No. 1,444

Term of patent 7 years

(Cl. D91—1)

FIG. 1 is a perspective view of a support for elongated tenuous articles embodying my new design;

FIG. 2 is a front elevational view of the front of the article seen in FIG. 1, the back being identical thereto;

FIG. 3 is a sectional view taken substantially along the line 3—3 of FIG. 2, and

FIG. 4 is a sectional view taken substantially along the line 4—4 of FIG. 2.

The support is symmetrical with reference to center line 3—3.

The dominant features of my design reside in the portions shown in full lines.

I claim:

The ornamental design for a support for elongated, tenuous articles, as shown and described.
